UNITED STATES PATENT OFFICE.

CARL H. SCHAFER, OF SHARPSBURG, PENNSYLVANIA, ASSIGNOR TO WESTINGHOUSE ELECTRIC & MANUFACTURING COMPANY, A CORPORATION OF PENNSYLVANIA.

PANTOGRAPH TROLLEY.

Application filed January 25, 1924. Serial No. 688,381.

My invention relates to pantograph trolleys, more particularly to pantograph structures and actuating mechanism to facilitate raising and lowering the collector shoes 5 thereof, relative to the overhead supply line.

It is among the objects of my invention to provide a pantograph structure of the air-actuated or spring-actuated type which shall be adapted to raise the trolley shoes 10 from their lowered position to their operative position in a direct and positive manner, which shall be of simple, compact, and durable mechanical construction, and which shall be provided with a plurality of rods 15 to initiate the upward movement of the pantograph device.

In modern types of pantograph structures, the pantograph frame sometimes comes to rest on or near dead center, which makes 20 it impossible to raise the frame with the standard actuating mechanism with which they are provided. In fact, when the frame is on dead center it will tend to reverse 25 its action and drop downward as the actuating mechanism is energized.

My present invention is directed to means for overcoming this difficulty comprising a plurality of arms that are secured to the operating shaft and that function to initiate the upward movement of the frame member, which is subsequently carried upward by the air-pressure or spring pressure, as the case may be, of the actuating means.

In the accompanying drawing constituting 35 a part hereof and in which like reference characters designate like parts;

Fig. 1 is a plan view with parts broken away of a pantograph structure embodying the principles of my invention, and

Fig. 2 is a side view thereof, with parts broken away to more clearly illustrate the actuating mechanism.

The structure in Fig. 1 comprises a structural or composite base 1 that is adapted 45 to be supported on a plurality of insulating pads 2, which are disposed intermediate the base 1 and the roof of an electrical vehicle, as is customary. A pair of pivot shafts 3 are mounted in parallel relation on the frame 1 to adapt them to carry an extensible pantograph structure, which comprises a plurality of substantially parallel-extending pipes or rods 4 that are suitably hinged

upon the usual intercrossing pipes 5 and connected to the shafts 3 by brackets 6. The 55 projecting ends of the shafts 3 are provided with mounting brackets 7 for securing helical springs 8, and a plurality of collector shoes 9 are mounted at the top of the pantograph in accordance with a familiar practice. 60 A pair of air cylinders 10 are mounted on the base in working relation with the actuating shaft 11. The shaft 11 is provided with a pair of cranks (not shown), which are pivotally connected to pistons that 65 are operatively disposed in the cylinders 10. A plurality of bell cranks 13 are secured on the shaft 11 and one end of each of said cranks is adapted to secure a corresponding rod 14 in position. 70 Each rod 14 has a portion 15 bent at right angles, that is parallel to the longitudinal axis of the collector shoes 9. The normal positions of the rods 14 are such as to prevent the shoes from dropping below a pre- 75 determined position that is above the center line of the pantograph structure, thereby preventing the latter from reaching or going below dead center.

The springs 8, which are connected at one 80 end to the corresponding end brackets 7 of the shafts 3, are secured at their opposite ends to the respective bell cranks 13, the springs functioning to return the pantograph to its lowered position when the air 85 pressure in the cylinders 10 is released.

The operation of this device is briefly as follows: When in its lowered and inoperative position, the pantograph structure assumes the position shown in Fig. 2. To 90 raise the collector shoes towards the trolley wire into their operative positions, air or other suitable fluid pressure is supplied to the cylinders 10 to actuate the piston members. The shafts 11 are thus caused to 95 rotate, thereby raising the rods 14, which engage the underside of the collector shoes 9, to actuate them upward, and they are further raised by the normal operation of the cranks 13. The rods 14 further function 100 to hold the pantograph frame in its operative position at all times. During the lifting of the pantograph, tension is applied to the helical springs 8.

When the air pressure in the cylinders 105 is released, the tension of the springs will

retrieve the pantograph mechanism, to lower the same to the position shown in Fig. 2.

It is evident from the foregoing description of my invention that a pantograph structure and actuating mechanism constructed in accordance therewith will provide an efficient and compact current-collecting apparatus, which functions positively to raise and lower the collector shoes 10 to their operative and inoperative positions, respectively.

Although I have described a specific embodiment of my invention, it will be obvious to those skilled in the art that various modifications may be made in the details of construction, such as the design and proportions of the several co-operating parts, without departing from the principles herein set forth.

20 I claim as my invention:—

1. A pantograph trolley structure comprising an extensible pantograph frame, spring means connected thereto to bias the same in one direction, fluid-pressure actuating means for said frame, and oscillatable lifting rods associated with said actuating means to initiate the movement of said structure.

2. A pantograph trolley structure comprising an extensible pantograph frame, spring means connected thereto to bias the same in one direction, fluid-pressure actuating means for said frame, and oscillatable mechanical means for initiating the movement of said pantograph structure from a dead center position.

3. A pantograph trolley structure comprising an extensible pantograph frame, a current collector mounted thereon, means 40 for raising said collector to its operative position, and longitudinally projecting arms associated with said raising means and

adapted to engage said collector to initiate the upward movement thereof.

4. A pantograph trolley structure comprising an extensible pantograph frame, 45 spring means connected thereto to bias the same in one direction, fluid-pressure actuating means for said frame, and lifting rods mechanically connected to said actuating means for engaging said frame to initiate the movement of the pantograph from a dead center position.

5. A pantograph trolley structure comprising an extensible pantograph frame, 55 spring means connected thereto to bias the same in one direction, fluid-pressure actuating means comprising a shaft for operating said frame, and lifting rods associated with said shaft for initiating the extension of 60 the pantograph.

6. A pantograph trolley structure comprising an extensible pantograph frame, spring means connected thereto to bias the same in one direction, an operating shaft 65 therefor, bell cranks mounted on the respective ends of said shaft, lifting rods connected to said cranks and operatively associated with said frame, and actuating means for said operating shaft.

7. A pantograph trolley structure comprising an extensible pantograph frame, an operating shaft therefor, cranks mounted on the respective ends of said shaft, springs associated with said structure and connected 75 to said cranks, lifting rods adapted to engage said structure and connected to said cranks, and actuating means for said operating shaft.

In testimony whereof, I have hereunto 80 subscribed my name this 15 day of January, 1924.

CARL H. SCHAFER.
